(57) **CLAIM**

We claim the ornamental design for a cooling air outlet for refrigerator, as shown and described.

DESCRIPTION

FIG. 1 is a front/top perspective view of a cooling air outlet for a refrigerator showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of said cooling air outlet in use.

The broken lines in the drawings are for environmental purposes only and form no part of the claimed design.
